IMPACT CRUSHER

Elman B. Myers, Montreal, Quebec, Canada

Application July 31, 1935, Serial No. 33,932

5 Claims. (Cl. 83—46)

My present invention relates generally to the crushing or disintegration of solid materials, and has particular reference to improvements in crushers of the so-called "impact" type.

It is well known that solid materials of frangible character, such as siliceous ores, talc, lime, pyrites, coal, and the like, if directed in the form of a high velocity stream against an anvil, are reduced in particle size. Various attempts have heretofore been made to harness this phenomenon to the comminution or pulverization of materials, but, because of various difficulties arising from faulty design and a failure to understand fully the underlying capabilities and shortcomings of high velocity gas streams, no really practical apparatus has ever, to my knowledge, been devised or employed.

In accordance with the present invention, I have successfully devised, constructed and operated an apparatus which is practical, effective in accomplishing its purposes, and efficient, from the standpoints of cost and operation, volume of production and rapidity and quality of resultant pulverization, in a variety of arts where cumbersome and expensive ball-mills, and the like, have been regularly and tediously employed for effecting a much less adequate degree of comminution.

Since apparatus according to my invention is admirably suited for the disintegration of free-milling ores, I have herein illustrated and described an installation designed primarily for this purpose. Nevertheless, it will be understood that the features of my invention adapt themselves with equal, and sometimes greater, facility and advantage to many other industries and purposes.

One of the features of my present invention lies in the successful obviation of the difficulty heretofore encountered in trying to effect an efficient and adequate merger of a stream of solids with a stream of high velocity gas. I have found that a gas stream flowing at high speed manifests characteristics of a solid in that it resists entry thereto. Accordingly, to attempt to feed solids laterally into such a stream is of no avail. On the other hand, to direct a stream of gas laterally, or even at most obliquities, into a mass of solid, results in building up undesirable back pressures which prevent smooth, continuous, practical operation.

In accordance with my invention, I first impart to the solids themselves a movement in the form of a stream, the particles being imbued with a kinetic energy which resists deflection. This I accomplish by feeding the material into the upper end of a vertical tubular barrel of adequate

length whereby the particles fall by gravity and form a stream of increasing velocity. Then, without decreasing the cross sectional area of the stream, I introduce a gas traveling at a high velocity, which smoothly merges with the stream of solid material. I have found that this can be done, without developing back pressures or otherwise impeding or impairing the smooth continuous flow of the solid, by introducing the gas in the form of a tapering conical stream, the apex angle of the cone being less than 10 degrees and preferably about 6 degrees. In the illustrative embodiment of the invention the gas is introduced at a midportion of the barrel hereinbefore mentioned.

Another feature of my invention lies in adequately providing the maximum opportunity for the solid material to acquire the higher velocity of the gas. I have found that this may be achieved by making the length of the barrel, from gas inlet to muzzle, at least 14 times as great as the internal diameter. If the length is less, the particles of solid material do not have an adequate opportunity to accelerate to the velocity of the gas stream; and if the length is too great velocity decreases.

My invention, furthermore, provides for accurate variation of the cross-sectional area of the gas stream admitted into the barrel. This provides a means for effective control of the quantity of gas employed, and this in turn enables the merger of gas and solids to be effected with maximum efficiency, depending upon the type, size and specific weight of the material which is to be crushed.

One satisfactory structural mode of accomplishing the foregoing objectives is to make the material guiding and confining portions of the barrel of two complementary sections of uniform internal diameter substantially throughout and having adjacent parallel surfaces which conform to a downwardly-tapering cone; the sections having micrometric threaded portions which engage with another portion of the barrel to provide a means for accurate relative axial adjustment of the sections. Such adjustment effects desired variations in the width of the annular space or gap between the sections, and a high pressure gas, preferably but not necessarily, air, is introduced into the barrel through said gap.

One of the structural features of my invention lies in providing a replaceable lining or sleeve, of special wear-resistant material at the muzzle of the barrel so as to withstand, for relatively long periods of time, the destructive abrasion of the

particles which emanate from the barrel at a high velocity.

Another feature of the invention lies in employing a gas at a pressure which will develop the maximum theoretical velocity in the barrel. With air, a pressure of approximately 500 pounds per square inch has been employed, the theoretical velocity of the air stream generated being approximately 1150 feet per second. A pressure higher than this will not produce any material increase in velocity, whereas too little pressure will be inadequate to overcome the inertia of the solid particles.

I achieve the foregoing objectives, and such other objectives as may hereinafter appear or be pointed out, in the manner illustratively exemplified in the accompanying drawings in which

Figure 1 is a diagrammatic elevational view of an impact crusher embodying the features of my present invention; and

Figure 2 is an enlarged longitudinal cross-sectional view through the barrel itself.

Referring to Figure 1, the barrel of the present apparatus is designated generally by the reference numeral 10, a funnel or the like 11 being mounted at the upper end, and the lower or muzzle end 12 being arranged over an anvil 13. The anvil and the muzzle end of the barrel are enclosed within a chamber 14 having an outlet opening 15 at its upper end and having an outlet conduit 16 at the bottom. The conduit 16 leads into a second chamber 17 which serves as a classifier. It contains a bed-plate 18 arranged beneath the lower end of the conduit 16, and is provided with the outlet opening 19 at its upper end and with the outlet chute 20 at the bottom.

Extending from the opening 15 is a conduit 21, and extending from the outlet opening 19 is a similar conduit 22, the latter conduits leading 40 into a tank 23, which may contain water. An agitator 24 is preferably arranged within the tank and may be operated by a motor 25, or the like. At the upper end of the tank I provide an inlet pipe 26, and an air vent 27; and at the bottom of the tank a pipe 28 serves as an outlet.

Before describing the details of the present barrel I will point out that the solid material, in the form of particles of free milling are for example approximately $\frac{3}{8}''$ - $\frac{3}{4}''$ in size, is fed continuously into the hopper 11, this feed being accomplished in any desirable or suitable manner. I have diagrammatically illustrated a traveling belt conveyor 29, adapted to deliver the material down a chute 30 into the funnel 11. However, any other suitable type of feeding mechanism may be employed and it is often preferable that the mechanism be of a character which gently agitates the particles as they are fed into the crushing apparatus. The stream of solid particles is discharged out of the muzzle 12 at a high velocity. The particles strike forcibly against the anvil 13 and the anvil is preferably provided with the replaceable plate 31 which is of special wear-resistant material such as chromium-manganese-iron.

This impingement of the particles against the anvil causes disintegration of a portion thereof, to a powder of a fineness less than 300-mesh. Approximately 60% of the powder mass has a size smaller than 5 microns, and some of the particles are even as small as one millimicron. These particles are obviously of air-float dimensions and most of them are withdrawn through the conduit 21. A baffle ring 32 arranged within 75 the chamber 14 serves to deflect the larger par-

ticles and causes them to travel downwardly through spaces 33 provided for this purpose in the anvil 13.

The gas and particles which pass downwardly through the conduit 16 are again deflected by the plate 18 and additional fine particles are recovered by passing outwardly through the conduit 22. The heavier particles are again deflected downwardly by the ring baffle 34, passing through openings 35 in the plate 18, and entering the chute 20. From here, these particles are led back to the hopper 11.

The pulverized ore material entering the tank 23 through the conduits 21 and 22 is captured in suspended form by the water or other liquid in the tank and this suspension is continuously drawn off through the outlet 28, from which point it may be led to other apparatus where the values may be recovered. In the case of the recovery of gold or similar values from ore, the material from the pipe 28 may be led directly to an amalgamation apparatus, or it may be preliminarily led to a colloid mill for further colloidization.

Referring now to Figure 2, I will point out the salient characteristics of my present invention, which permit the foregoing illustrative operation to be carried out in a practical, continuous, and economical manner.

The barrel 10 is composed of two sections, the upper section 36 having a flange 37 secured to the funnel 11, and having also a portion 38 provided with the micrometric screw threads 39. The internal diameter is uniform throughout, except near the top where it enlarges somewhat to facilitate the admission of the solid particles. At the lower end of the section 36 the outer surface is downwardly-tapered, as shown at 40, thereby conforming this surface to a downwardly-tapering cone having an apex angle no greater than 10 degrees and preferably 6 degrees.

The lower section 41 of the barrel is aligned with the upper section and has an internal diameter not less than that of the upper section. The upper portion of the section 41 has its inner surface 42 downwardly-tapered so that it forms a complementary parallel surface, relative to the tapered surface 40 of the upper section. This permits the two sections to define an annular conical passage-way 43 which serves for the admission of the high pressure gas in a downwardly-tapering conical stream.

At its lower end the section 41 is provided with a replaceable sleeve or lining 44 which is preferably of nickel-chromium-iron or boron carbide or similar wear-resistant material. This lining is held in place, in a replaceable manner, by means of the ferrule 45. The opening 46 of the ferrule is purposely larger than the internal diameter of the barrel so that passage of the solid material, at high velocity, will exercise abrasive action if any against the lower corners 47 of the lining.

Carried by the lower section 41 is a gas-inlet manifold 48 which communicates with the upper end of the passageway 43. Gas at high pressure is admitted through the opening 49. The manifold 48 may, if desired, be formed integrally with the section 41, but it is preferable to employ a threaded engagement, as indicated at 50, so that the lower section 41 of the barrel may be completely replaceable, if desired. In effect, the manifold 48 forms a part of the lower section 41, and is provided with micrometric screw threads which engage with the threads 39 hereinbefore

mentioned. The reference numerals 51 and 52 designate lock nuts.

In accordance with my invention, the width of the gap 43 may be accurately controlled, and may be adjusted from a zero width to any selected size suitable for the gas employed, the pressure used, and the general purpose of the apparatus. This adjustment is effected by rotating the upper section 36, and by virtue of the micrometric threads 10 39, each complete rotation corresponds accurately to a definite alteration in the width of the gap 43. In this way varying amounts of gas may be introduced to meet different operating conditions.

Another feature of my invention, as hereinbefore mentioned, lies in the proportioning of parts so that the distance from the gas-inlet 43 to the muzzle end of the barrel is at least 14 times as great as the internal diameter. This affords opportunity for the high velocity gas to accelerate the solid particles up to effective velocities 20 20 to disintegrating the particles on impact.

Because of the unconstricted barrel and the acute angle of the conical passage 43, in combination with the adequate relative length of the barrel 25 from gas-inlet to muzzle, the apparatus may be continuously employed in a highly efficient manner. A continuous crushing of certain kinds of material at the rate of 10 tons per hour may, for example, be carried on by employing air at 30 not over 500 pounds' pressure and in a quantity of not over 600 cubic feet per minute. For such an output the length of the barrel, from gas-inlet to muzzle, was approximately 28 inches, and the internal diameter approximately 2 inches. The 35 gas-inlet passageway 43 is of appropriate cross-sectional area to provide the proper volume of air and the anvil 13 is arranged about 6 inches away from the muzzle. In using a barrel of the above dimensions and with the gas inlet angle as above 40 set forth, the optimum position will be substantially that shown in Figure 2 of the drawings and the width of the inlet opening will be approximately .036 inch.

The foregoing relative dimensions are given 45 merely for the purpose of explaining the general nature of the invention and it will be obvious that variations may be made to suit differing requirements. For example, another successful installation employs an internal diameter of about 1 50 inch, a length of barrel, from gas-inlet to muzzle, of approximately 18 inches, and an optimum gas-inlet gap of approximately .026 inch. Such an arrangement of parts employs about 264 cubic feet of air per minute, at 500 pounds' pressure, and 55 crushes three tons of certain kinds of material per hour.

Various uses to which the present apparatus may be put will be obvious to those skilled in the art, but I wish to point out that, in addition to 60 the crushing of ores, and the release of metallic values, such as copper, gold, silver, platinum, palladium, and the like, from quartz or similar materials, the apparatus is admirably suited for widely different purposes, notably the pulverization 65 of coal.

Similarly, in the cement industry, the cement clinkers developed during the roasting process may be efficiently and inexpensively reduced to powder by the present apparatus, thereby obviating the necessity for the regular expensive and cumbersome employment of ball-mills, pebble-mills or the like.

Generally speaking, various advantages of the present apparatus may be summarized as follows:

75 The gross weight, including the air-com-

pressing machinery, is markedly less than that of conventional equipment of equivalent output capacity.

The initial cost of the present apparatus is much less than that of conventional mills; and 5 the upkeep and maintenance costs are negligible compared to conventional costs.

Reduction in particle size of various materials may be effected in the dry state.

The space required by the illustrated apparatus 10 is relatively small. The chamber 14 and the chamber 17 of Figure 1 occupy little over 10 feet in height and about 4 feet in width. The tank may be as little as 7 feet in diameter and 6 15 feet high.

There are no moving parts, and the elements subject to wear may be easily replaced.

In general, it will be understood that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting 25 sense.

Having thus described my invention, and illustrated its use, what I claim as new and desire to secure by Letters Patent is—

1. In an impact crusher, a barrel comprising 30 separate coaxially arranged upper and lower sections, said upper section having an outer conical surface tapering at an angle of less than five degrees to its longitudinal axis and said lower section having an inner conical surface and a 35 cylindrical bore, said inner surface being arranged opposite said outer conical surface and parallel thereto to form an annular conical passage opening into said lower section, and said cylindrical bore extending continuously from 40 said conical passage to the discharge end of said lower section, means for feeding material to be crushed through said upper section into said lower section, means for delivering gas under pressure into said cylindrical bore through said 45 conical passage, and an anvil opposite said discharge end of the lower section.

2. In an impact crusher, a barrel comprising 50 separate coaxially arranged upper and lower sections, said upper section having an outer conical surface tapering at an angle of less than five degrees to its longitudinal axis and said lower section having an inner conical surface and a cylindrical bore, said inner surface being arranged opposite said outer conical surface and parallel 55 thereto to form an annular conical passage opening into said lower section, and said cylindrical bore extending continuously from said conical passage to the discharge end of said lower section, the length of said continuous cylindrical 60 bore being at least fourteen times its diameter, means for feeding material to be crushed through said upper section into said lower section, means for delivering gas under pressure into said cylindrical bore through said conical passage, and an 65 anvil opposite said discharge end of the lower section.

3. In an impact crusher, a barrel comprising 70 separate coaxially arranged upper and lower sections, said upper section having a outer conical surface tapering at an angle of less than five degrees to its longitudinal axis and said lower section having an inner conical surface and a cylindrical bore, said inner surface being arranged opposite said outer conical surface and parallel

thereto to form an annular conical passage opening into said lower section, and said cylindrical bore extending continuously from said conical passage to the discharge end of said lower section, one of said sections being adjustable in relation to the other to vary the effective width of said passage, means for feeding material to be crushed through said upper section into said lower section, means for delivering gas under pressure into said cylindrical bore through said conical passage, and an anvil opposite said discharge end of the lower section.

4. In an impact crusher, a barrel comprising separate coaxially arranged upper and lower sections, said upper section having an outer conical surface tapering at an angle of less than five degrees to its longitudinal axis and said lower section having an inner conical surface and a cylindrical bore, said inner surface being arranged opposite said outer conical surface and parallel thereto to form an annular conical passage opening into said lower section, and said cylindrical bore extending continuously from said conical passage to the discharge end of said lower section, the length of said continuous cylindrical bore being at least fourteen times its diameter, one of said sections being adjustable in relation to the other to vary the effective width of said passage, means for feeding material to be crushed through said upper section into said lower section, means for delivering gas under pressure into said cylindrical bore through said conical passage, and an anvil opposite said discharge end of the lower section.

35 5. Apparatus for crushing material by impact

wherein said material is supplied to an acceleration tube through a feed tube having its delivery end extending centrally into the inlet end of said acceleration tube and is accelerated therein by gas under pressure and discharged therefrom in an unimpeded stream against an anvil arranged opposite the discharge end of said acceleration tube at sufficient velocity to be crushed by impact with said anvil, characterized in that said delivery end of the feed tube has an outer surface disposed at an angle of less than five degrees to its longitudinal axis and said inlet end of the acceleration tube has an inner surface arranged in opposed spaced parallel relation to said outer surface and forms therewith in effect an injector nozzle passageway for supplying gas under pressure to said acceleration tube in an annular stream laterally enclosing the path of material delivered centrally into said acceleration tube through said feed tube, and said acceleration tube has an acceleration and discharge end portion provided with a bore of a length at least fourteen times its diameter and of substantially undiminished cross-sectional area in the direction of movement of material therethrough, which cross-sectional area is substantially the same as that of the bore of said delivery end of the feed tube, and with its discharge opening arranged opposite the anvil to discharge material freely from the delivery end of said feed tube into crushing impact with the anvil in an unimpeded stream of undiminished cross-sectional area from said delivery end of said feed tube to the impact surface of said anvil.

ELMAN B. MYERS. 35
